UNITED STATES PATENT OFFICE.

THOMAS S. CRAPP, OF INDIANAPOLIS, INDIANA, ASSIGNOR OF ONE-HALF
TO ROBERT C. FINCH, OF INDIANAPOLIS, INDIANA.

CARD-DISPLAYING APPARATUS.

No. 814,588.

Specification of Letters Patent.

Patented March 6, 1906.

Application filed June 27, 1904. Serial No. 214,359.

To all whom it may concern:

Be it known that I, THOMAS S. CRAPP, a citizen of the United States, residing at Indianapolis, in the county of Marion and State of Indiana, have invented certain new and useful Improvements in Card - Displaying Apparatus, of which the following is a specification.

This invention relates to means for exhibiting in a successive order cards showing advertising matter, photographs, pictorial illustrations, and designs and characters of all kinds printed, painted, or impressed by any known means on said cards.

The object of the invention is to positively and automatically present the cards opposite a display-opening in an advertising-cabinet in the order of their succession without any interference with one another and so the cards will always stand square and plumb with the cabinet—that is, not higher at one end than at the other—also to provide means for correcting such or any irregularities of movement and to provide a simple, durable, and inexpensive mechanism that will be compact, so as to require a cabinet of minimum dimensions to inclose it. These objects are accomplished by the mechanism illustrated in the accompanying drawings, in which—

Figure 1 is a perspective view of the cabinet in which the cards are placed and displayed; Fig. 2, a transverse vertical section of the invention; Fig. 3, a like view of the top part of the invention on a larger scale; Fig. 4, a cross-section on the line 4-4 of Fig. 3 looking down; Fig. 5, a plan view, and Fig. 6 a rear elevation, of the circuit maker and breaker for flashing the lights used for illuminating the cabinet; Fig. 7, a detail in side elevation of one of the circuit-breakers used in said flashing mechanism; Fig. 8, a detail inside view of the end wall of the cabinet, showing a dog and the top and front-frame-grooves and mechanism for receiving- and discharging the frames; Fig. 9, a section on the line 9-9 of Fig. 8. Fig. 10 is a longitudinal section of a dog and adjacent portion of the band to which the dog is attached; Fig. 11, a front view of same, and Fig. 12 a view of the band with the dog removed. Fig. 13 is a detail in cross-section of the rod to which the frame to support the card to be displayed is attached, and Fig. 14 is a detail showing the mechanism by which the extension of le-

vers into the path of the vertically-moving card-holders is regulated.

Like characters of reference indicate like parts throughout the several views of the drawings.

1 is a cabinet in which the operative mechanism of my invention is mounted. It has the front display opening or window surrounded by a frame 2, on which are mounted the incandescent lamps 3 and 4, the light from which is reflected, by means of the reflectors 5, against the faces of the advertising-cards as they are presented opposite the display-opening. The reflectors give support to the glass 6. Surrounding the frame 2 are openings in which the ornamental glasses 7 are mounted, and these are illuminated by means of the electric lamps 8, having bulbs of assorted colors, the current to which is intermittent, so as to "flash" the lights. This flashing mechanism is illustrated in Figs. 2, 5, 6, and 7, in which 9 is a frame mounted on the bottom of the cabinet and supporting the shaft 10. Mounted on said shaft is the worm-wheel 11, which is driven by the worm 12, and the latter has the pulley 13, which is driven by belt from any suitable power, preferably an electric motor. (Not shown.)

14 is a bar of insulation supported by the frame 9 and having the pivoted vertically-movable terminal levers 15, here shown as three in number, which are connected electrically with the respective lamps in series of three colors. Below the bar 14 is the shaft 16, having the pairs of spring-terminals 17. The shaft is part of an electric circuit which is made and broken by connecting and disconnecting the two terminals above mentioned. This contact is made by heads on ends of arms 18, mounted on revolving shaft 10, being brought into contact with the terminal levers 15, thereby forcing the levers down into contact with the terminals 17 and holding the contact till the said heads have passed, thereby releasing levers 15, whereupon they are raised out of contact with terminals 17 by springs 19 and the circuit broken.

Formed in the sides or ends of the cabinet are the vertical front grooves 20 and rear grooves 21, parallel with said front grooves. These are connected at their tops at each end of the cabinet by the grooves or gravity-runs 22, which slope from front to rear, and at

their bottoms by the grooves or runs 23, which slope from the rear downwardly to the front.

Mounted inside of the cabinet near its top 5 is the shaft 24, which is parallel with the cabinet-front. Its journal-boxes are supported on the levers 25, which are pivoted to the ends of the cabinet at their front ends and are supported at their rear ends on the set-screws 26, whereby a vertical adjustment of the shaft is obtained at either or both ends. Secured to the ends of the cabinet are the shaft-stubs 27. Mounted on said stubs and above on the shaft 24 are the wheels 28, upper and lower ones of which form pairs which are connected by the endless metal bands 29, having longitudinal slots to receive pins 30, radiating from the peripheries of the wheels. The pins may be omitted from the lower 20 wheels, if preferred. The object in having longitudinal slots instead of round holes is to enable the belt to slide somewhat longitudinally, and thereby adjust itself, and to facilitate this the ends of the pins are made tapering to act as wedges. The bands are tightened to prevent lateral vibration by adjusting the top shaft and its band-wheels vertically by means of the levers and set-screws above described. While a band belt has 25 been shown, it is not desired to limit the invention thereto, as it is obvious that a link belt may be employed, and in some cases—as, for example, the large-size machines for window exhibits—may be preferable.

30 One of the lower wheels is provided with the sprocket-wheel 31, which is connected by the chain belt 32 with the sprocket-wheel 33 on the shaft 10, and through said chain belt and adjacent band 29 the top shaft 24 is rotated, and by the rotation of said top shaft its wheel 28 on the opposite side of the cabinet is revolved, thereby causing its band 29 to travel uniformly with its opposite mate. Secured to the belts or bands 29 are the carriers 34, (here shown as two in number for each band or belt,) which are provided for the purpose of receiving the supporting-bars 35 of mediums for the display of matter to be exhibited, here shown as the card-holding 35 frames 36, as they are discharged from groove 23 and carrying them up to groove 22 in front of the machine and for receiving said bars from groove 22 at the rear of the cabinet and carrying them down to the groove 23. 40 At the places of attachment of said carriers to the bands are the eyes 37 in pairs, as shown in Fig. 12. Each of the carrier-bodies is formed from sheet metal bent U shape in cross-section to receive its respective band 45 between its side members, as clearly shown in Fig. 9. These side members have opposite perforations near one end to receive a pin 38, which is passed through the eyes 37 and then through said perforations, thereby 50 forming a hinged connection of the carrier with its band. This pin has the U-shaped bend 39, and it is made from spring-wire, so as to permit the ends to be pressed inwardly, thereby permitting the attachment and removal of a carrier at a moment's notice without dismantling other parts of the machine. This is an important feature of my invention, as it permits of quick repairs in cases of accident and wear. The sides of the carrier at the opposite end from the perforations are 55 widened to form the extensions 40, which reach toward the inside of the cabinet across the slots 20 and 21, thereby forming supports or holders which receive the supporting-bars 35 as the latter are discharged from the runs 60 22 and 23. The supporting-bars 35 are horizontal and extend transversely of the cabinet parallel with the front of the latter and are of such length that their ends extend into the grooves. The bars are round, and the card-holding frames 36 are suspended therefrom by means of loops 37 at the tops of the vertical members of the frames, so as to swing freely from said bars. (See Fig. 13.)

65 The carriers 34 are held close to their bands 60 and in operative position by the springs 41, which also serve to hold the bends 39 of the pins 38 down against the bands. The hinged attachment of the carriers allows them to swing away from the bands into tangential 70 positions while passing around the wheels 28. The supporting-bars 35, which are loosely supported by the grooves 23, descend by gravity to the lower ends of the grooves and are discharged *serialiter* into the lower ends of 75 the vertical grooves 20. Being then in the paths of the carriers on the upwardly-moving members of the endless bands, said supporting-bars are carried to the tops of grooves 20, where they are pushed into the 80 vertical grooves 22 by the springs 42. These latter have the angular bends 43, which keep the rods from working back after the angle formed by the bend has been passed, which occurs 85 after the carriers have been withdrawn by 90 the engagement in the switch 44 of the lateral ears 45, projected from the outer free end of said carriers, as clearly shown in Figs. 8, 9, and 10. After being deposited in the groove 22 the supporting-bars 35 are moved 95 by gravity to the lower end of the oblique groove 22, and they would all be discharged 100 into the vertical groove 21 but for the spring 105 46, which, as shown in Fig. 8, bears down upon the top of the lowest one of said bars. The tension of the spring 46 is regulated by 110 the set-screw 47, and the holding power of the spring is overcome by the upward-and-rearward movement of lever 48. The levers 48 are moved by the upwardly-traveling supporting-bar at the front of the cabinet acting 115 through suitable mechanism. This mechanism comprises a lever 49, having an end projecting across groove 20 in the path of the supporting-bar, being carried up at the front 120 130

of the cabinet. The lever 49 is pivotally secured near its inner end to the plate 50 (see Fig. 14) and is held normally down against the rubber bumper 51 by the spring 52. The plate 50 is fastened to the ends of the cabinet by screws at each end, as shown. The upper one passes through a transverse slot 53, which permits of a lateral swinging adjustment of plate 50, whereby the extent of projection of lever 49 into the path of the supporting-bar is regulated. The lever 49 is connected by bar 54 with the lever 48, and the above mechanism is timed so that lever 48 is tripped and discharges its supporting-bar just as the downwardly-moving carrier has passed the mouth of groove 22 and is in position to receive it. The bar 54 has the oblique slot 60, through which the pin 58 passes and enters the wall of the cabinet. A spring 59 is coiled around the pin 58 and has one end driven into the cabinet, while the other end bears against the edge of the bar 48, pressing that bar in an upward direction. The upper corner of the bar or lever 48 is pointed to permit it to enter readily between and separate the bars 35, and this positive separation and holding of the bars 35 is retained by the pin 62 until by the longitudinal movement of the lever 48 a notch 61 on its underside receives the pin 62 and allows the lever 48 to be pressed down out of the path of the bar 45 in the groove 22. A similar mechanism like that shown in Fig. 14 and just described, except that it is inverted, is used to longitudinally reciprocate the tapered holding-bar 55, which restrains the supporting-bars and allows only one at a time to discharge at proper intervals from the grooves 23.

The frame 2 has the screen-plates 56 56 at top and bottom to obstruct the view of the interior of the cabinet through the front window at the top and bottom of the display-cards, and secured to the bottom member of said frame 2 is the spring 57, which presses the lower portion of each card inwardly of the cabinet, so as to obviate the possibility of an ascending card going behind instead of in front of its preceding card.

Having thus fully described the invention, what is claimed as new and useful, and desired to be covered by Letters Patent of the United States, is—

1. In a card-displaying apparatus, the combination with a cabinet having sides with opposing front and rear vertical grooves, and having a rearwardly-sloping groove connecting their tops and a groove connecting their bottom ends which slopes downwardly toward the front, of card-supporting bars adapted to be supported at their ends in said top and bottom inclined grooves, a friction-spring to press against the bars in the top groove to regulate their movement therein, means to regulate the tension of said spring, of endless conveying-belts having

their vertically-extending portions opposite said vertical guideways, means for moving said belts in a forward direction and carriers mounted on said belts.

2. In a card-displaying apparatus, the combination with a cabinet having sides with opposing front and rear vertical grooves, and having a rearwardly-sloping groove connecting their tops and a groove sloping toward the front connecting their bottoms, of card-supporting bars adapted to be supported at their ends in said top and bottom inclined grooves, means for discharging said bars *seriatim* into said vertical grooves, carriers moving in a constant upward direction past the front vertical grooves and downwardly adjacent the rear vertical grooves to carry said bars between said inclined grooves, a spring at the top of the front vertical grooves to discharge the bars into the top inclined groove and a switch opposite the entrance to said top inclined groove to withdraw the carriers from the bar being discharged from the vertical to the inclined groove.

3. In a card-displaying apparatus, the combination with a cabinet having sides with opposing front and rear vertical grooves, and having rearwardly-sloping grooves connecting the tops of said vertical grooves and forwardly-sloping grooves connecting their bottoms, of card-supporting bars adapted to be supported at their ends in said top and bottom inclined grooves, carriers moving constantly upward past the front vertical grooves and downward past the rear vertical grooves to carry said supporting-bars, levers pivoted at the discharge ends of the top inclined grooves having ends projecting in the path of the supporting-bars to restrain the latter, pivoted levers at the front of the apparatus having ends projecting in the path of the upwardly-carried supporting-bars whereby they are tripped, said last levers being connected with the first-mentioned levers and a spring to return them to a normal position.

4. In a card-displaying apparatus, the combination with a cabinet having sides with opposing front and rear vertical grooves, and having rearwardly-sloping grooves connecting the tops of said vertical grooves and forwardly-sloping grooves connecting their bottoms, of card-supporting bars adapted to be supported at their ends in said top and bottom inclined grooves, carriers moving constantly upward past the front vertical grooves and downward past the rear vertical grooves to carry said supporting-bars, pivoted levers at the lower ends of the top inclined grooves to restrain the discharge of said bars, a longitudinally-movable bar having a wedge-shaped lower end to restrain and regulate the discharge of said supporting-bars from the lower inclined groove, pivoted levers having ends projecting in the path of the

upwardly-moving supporting-bars and moved thereby, some of said levers being connected with the restraining-levers at the ends of the top grooves and other of said levers being connected with the longitudinally-movable bars, and means to return the said tripping-levers to normal positions.

5. In a card-displaying apparatus, a cabinet having sides with runs or grooves forming an endless circuit, card-supporting bars having ends inserted in said grooves, means for moving said bars intermittently in the same direction in said grooves, means to regulate the movement of said bars in said grooves so their movement will be intermittent but regular, and means to operate said last means comprising a plate secured by end screws said plate having a transverse perforation for one of said screws to permit lateral adjustment of said end, a lever pivoted to said plate and extending into the vertical path of said moving supporting-bars, a stop to arrest the downward movement of said lever, a spring to hold it against the stop.

25. 6. In a card-supporting apparatus, the combination with a cabinet having sides with opposing front and rear vertical grooves and having rearwardly-sloping grooves connecting the tops of said vertical grooves, and forming rearwardly-sloping grooves connecting their bottoms, of card-supporting bars adapted to be supported at their ends in said top and bottom inclined grooves, bar-retaining stops situated at the lower ends of said inclined grooves, a shaft, band-wheels on said shaft, band-wheels, directly beneath said band-wheels, some of said band-wheels having radial peripheral pins, endless belts connecting said upper and lower band-wheels, and opposite said forward and rearwardly extended guideways, said belts having longitudinal slots to receive the band-wheel pins, bar-carriers yieldingly mounted on said belts, and means for moving said belts in one direction.

45. 7. In a card-displaying apparatus, the combination with a cabinet having sides with opposing front and rear vertical grooves, and having rearwardly-sloping grooves connecting the tops of said vertical grooves and forming rearwardly-sloping grooves connecting their bottoms, of card-supporting bars adapted to be supported at their ends in said top and bottom inclined grooves, bar-retaining stops situated at the lower ends of said inclined grooves, a shaft situated above said inclined top grooves, levers pivoted at their ends on which said shaft is mounted and means to raise and lower the opposite or free ends of said levers to adjust the height of the shaft, 50 band-wheels on said shaft, band-wheels directly beneath said upper band-wheels, endless belts connecting said upper and lower band-wheels and opposite said forward and rearward vertically-extending guideways, bar-carriers yieldingly mounted on said belt

and means for moving said belts in the same direction without intermission.

8. In a card-displaying apparatus, a cabinet having a front window, carriers moving inside of the cabinet vertically past said window, horizontal supporting-bars carried by said carriers, display mediums suspended from said bars and springs at the bottom of the window to press the bottoms of the passing display mediums inwardly of the cabinet to insure that each one shall pass in front of the one preceding it.

9. In a card-displaying apparatus, a cabinet having endless grooves, card-supporting bars having ends entering the grooves in the opposite ends of the cabinet, card-frames suspended by hooks from said bars, carriers to carry the supporting-bars in vertical directions and means for pressing the lower end of an upwardly-moving card inwardly out of the path of the supporting-bar following it.

10. In a card-displaying apparatus, a pair of endless belts moving in a constant direction, horizontal card-supporting bars, located within the area inclosed by said belts, carriers hinged at one end of each to the outer face of its respective belt said carriers having extensions at their opposite ends which project inwardly past the belt and means for depositing the bars in consecutive order on the carriers and for removing them therefrom.

11. In a card-displaying apparatus, carrying-belts, carriers hinged at their ends to the outer faces of the belts, springs to hold their opposite ends normally in close contact with their respective belts said opposite ends having projections on each side of its belt which extend in past the belt to form supports for card-supporting rods.

12. In a card-displaying apparatus, carrying-belts having eyelets in horizontal pairs on their outer faces, pins located therein having elastically-expanded ends and carriers having perforated side members to receive the expanded ends of said pins.

13. In a card-displaying apparatus, carrying-belts having eyelets in horizontal pairs on their outer faces, pins located therein having U-shaped bends between said eyelets, carriers having perforated side members which are removably secured to said pin ends said side members being continued at the opposite end of the carrier from said perforations to form supports for card-supporting rods.

14. In a card-displaying apparatus, carrying-belts having eyelets in horizontal pairs on their outer faces, pins located therein having U-shaped bends between said eyelets, carriers having perforated side members to receive the ends of said pins and a spring secured to the carrier and bearing against the U-shaped bend of the pin to hold the carrier elastically against the band.

15. In a card - displaying apparatus, the combination with a cabinet having sides with opposing front and rear vertical grooves, and having rearwardly-sloping grooves connecting the tops of said vertical groove and forwardly-sloping grooves connecting their bottoms, of card - supporting bars adapted to be supported at their ends in said top and bottom inclined grooves, endless conveying belts having vertically-extended portions opposite said vertical grooves, means for moving said belts continuously in the same direction, a switch at the top of the front vertical groove opposite its junction with the top inclined groove, carriers hinged at one of their ends to said belts, a spring for each carrier to hold it normally in close contact with its belt and lateral extensions from said carriers at opposite ends from their pivoted ends, to enter said switch.
16. In a displaying device, a cabinet having endless grooves, supporting-bars having ends entering said grooves and means for traversing the bars therein, and a device for regulating the discharge of said bars from a transverse to a vertical groove comprising a longitudinally-moving bar having a diagonal slot, a stationary pin in said slot, a lever pivoted to the end of the bar having a pointed end and an under side notch, a spring pressing the pointed end of the lever between the supporting-bars and a second stationary pin to hold the lever in position between the supporting-bars except when the notch in said lever is opposite the pin.
- 18th day of June, A. D. 1904.
